[57] CLAIM

The ornamental design for a cup lid, as shown and described.

DESCRIPTION

FIG. 1 is a perspective view from above showing a cup lid showing our new design with the disk thereof rotated to an open position;

FIG. 2 is a top plan view thereof;

FIG. 3 is a bottom plan view thereof;

FIG. 4 is a side elevational view thereof;

FIG. 5 is a longitudinal sectional view thereof on line 5—5 of FIG. 2; and,

FIG. 6 is a top plan view similar to FIG. 2, but showing the disk thereof rotated to a closed position.

FIG. 1

FIG. 2

FIG. 3FIG. 4FIG. 5

FIG. 6
